UNITED STATES PATENT OFFICE.

GEORGE T. CHAPMAN, OF PITTSBURGH, PENNSYLVANIA, ASSIGNOR TO CENTRAL ELECTRIC TOOL COMPANY, A CORPORATION OF PENNSYLVANIA.

ROTATING DRILL CHUCK FOR PERCUSSIVE TOOLS.

Application filed November 17, 1924. Serial No. 750,236.

My invention relates to rotating chucks for use with percussive tools.

The object of my invention is to provide a rotating chuck that will rotate a drill 5 operated by a percussive tool to drill holes in stone, concrete, etc.

Another object of my invention is to obviate the necessity of a rotating wrench which has been heretofore used to rotate 10 the drill while a hole was being drilled thereby. In drilling holes in stone, concrete or similar materials, the drill of the usual type employed for this purpose must be rotated while being struck. The necessity for rotating a drill while striking it is that in its 15 action it operates as a rotating chisel, chipping off, bit by bit, the stone or other material upon which the cutting surfaces impinge, in such manner as to cut or chip a 20 hole in the material.

When actuated by percussive tools of the electric hammer type, it has been customary to rotate the drill by means of a rotating wrench. The operator held the hammer in 25 one hand and the rotating wrench in the other, thus giving him a two point support for the hammer. It was necessary, however, to rotate the wrench which constituted one of such two points. While this was 30 not an extreme disadvantage when drilling holes downward, as in a floor, it was somewhat of a disadvantage when drilling holes horizontally into a wall, or vertically into a ceiling. Even when drilling into a floor, 35 there was some disadvantage due to the fact that it was necessary to move the rotating wrench continuously through an angle of substantially ninety degrees where a drill with four flutes was employed. If the drill 40 was not turned fast enough there was liability of the drill jamming and necessitating the stopping and re-starting of the hammer, with a consequent delay in drilling.

By means of a rotating chuck of the character which I provide, the drill is automatically rotated while it is struck by the hammer, and the operator is enabled to devote his entire attention to supporting the hammer at the proper position.

The chuck which I provide comprises a striking element or anvil which is subjected to the striking force of the hammer or percussive tool. A housing enclosing the striking surface of the anvil supports a bearing 50 through which a tool socket extends into

the housing, exposing an impact receiving surface to the striking surface of the anvil. A circular jaw is disposed on a flange of the socket and surrounds the anvil within the housing. The circular edge or rim of 60 the jaw is provided with teeth, which two pawls supported on the inside of the housing engage. When the anvil is caused to strike the tool socket, the pawl actuates the tool socket, by means of the teeth, to rotate 65 the socket and the drill while the force of the blow acts upon the drill to cause it to do work. In order to prevent the weight of the hammer or percussive tool from pressing the anvil down against the tool socket, 70 and also to enable the pawls to assume new active positions to engage subsequent teeth, a helical spring is disposed to normally separate the anvil and the impact receiving surface of the tool socket. 75

Fig. 1 of the accompanying drawings is an elevational view illustrating the arrangement of a rotating chuck in a percussive machine of the electric hammer type;

Fig. 2 is a longitudinal view, partially 80 in section and partially in elevation of the chuck embodying my invention;

Fig. 3 is a vertical sectional view of the housing on the chuck;

Fig. 4 is a bottom view of the housing 85 illustrated in Fig. 3; and

Figs. 5 and 6 are respectively plan and side elevational views of the pawls employed in the chuck.

In Fig. 1 is merely illustrated a percus- 90 sive machine or the electric hammer 1 which acts upon the drill 2 through a chuck 3 to rotate the drill while causing it to drill holes in the material being worked upon.

The chuck 3 is illustrated in a specific 95 form by Fig. 2 and comprises, in general, an anvil 5, a housing 6, a bearing 7, a tool socket 8, a spring 9 and a pawl 10 for engaging teeth 11 on a circular jaw constituting part of the socket 8.

The anvil 5 comprises a shank 15 of hexagonal shape for receiving an impact force from the hammer, a striking surface 16 for transmitting the impact force and a threaded portion 17 backed by a shoulder 18 105 to permit the anvil to be securely threaded into the housing 6.

The housing 6 is of circular cup-shape having the anvil 5 threaded into the base thereof. The base is provided with a raised 110

inner portion 19 which serves as a guide for the pawl and acts as a seat for the spring 9. In the opening of the housing 6 is threaded a supporting flange 20 for the bearing 7 which is then tightly secured to the housing by means of a machine screw 21 and lock washer 22.

The tool socket 8 comprises a guide 23 for the drill, having an opening therethrough, 10 the upper portion of which is of hexagonal shape to preclude relative movement between the drill and the socket. A flange 24 on the end of the guide 23 of the socket constitutes both an impact surface for the anvil 15 and a seat for the spring 9. A circular jaw 25 disposed on the flange 24 surrounds the spring 9 and engages the inner surface of the housing 6. The upper circular edge or 20 end surface of the jaw 25 is provided with teeth 11 which are adapted to be engaged by the pawl 10.

The pawl 10 is pivoted on a pin 26 supported in the seat 19 of the housing. A spring 27 seated in the housing engages a 25 tip 28 on the heel of the pawl and serves to maintain the pawl in engagement with the toothed surface of the circular jaw of the tool socket.

Only one pawl is illustrated in the figure 30 but in the present chuck I employ two pawls each of which is alternately operative to engage a tooth and rotate the tool socket. Where it is desirable to provide larger teeth in the jaws in order to obtain greater 35 strength, the number of pawls may be increased. For example, if half the number of teeth are employed the same speed of rotation will be obtained by doubling the number of pawls. The manner in which the 40 pawls are secured in position will be understood upon considering Figs. 3 and 4 which illustrate the construction of the housing. Holes 30 and 31 are drilled through the side 45 of the housing into the seat 19. Each pawl is then placed in proper position to receive a pin or shaft 26 which may then be suitably secured in position to prevent it from falling out during operation of the hammer upon the chuck.

50 Openings 32 and 33 are provided in the housing directly above the shafts 26 and are adapted to receive oil cups or valves through which the shafts 26 may be oiled to permit free movement of the pawls.

55 Two small recesses 34 and 35 are provided in the seat 19 of the housing and are adapted to retain in position one end of the springs 27 which rests against the heels of pawls.

60 The pawls are formed from cylinders of approximately the same diameter as the circular jaw 25 on the tool socket. The curvature of the pawls thus corresponds to that of the circular jaw 25.

65 When the operator starts the hammer 1,

by closing the trigger switch 40 in the handle, a striking element, which in this case is a core reciprocating between two solenoids (not shown), strikes the end of the shank 15 of the chuck. The kinetic energy of the 70 striking element is imparted to the handle 5 which moves downward against the compression force of the spring 9 and strikes the force-receiving surface 36 of the tool socket 8. The force of this blow is transmitted to the drill 2 by the inside shoulders 37 of the tool socket. The shank of the drill should be hexagonal in shape to fit the hexagonal opening 38 of the tool socket 8. The end of the shank of the drill should not extend above the impact receiving surface 36. 80

As the anvil 5 has moved downwardly under the force of the blow, the housing 6 has acted upon the pawl 10 to cause it to push against one of the teeth 11 of the tool 85 socket to thereby turn the socket through a corresponding angle. With each recurring blow, the socket is turned a distance corresponding to half the tooth pitch. After the working energy of each blow is transmitted to the tool or drill, the spring 9, by reason of its compressed condition and the backlash of the hammer, raises the anvil and the housing to its initial position at which it is 90 ready to receive the next blow from the striking element of the hammer. When the anvil is restored to its initial position, one pawl or the other slips back and notches behind the next succeeding tooth by means of which it is to rotate the tool socket. When 95 the chuck is again struck, the blow is transmitted to the drill through the tool socket and at the same time the pawl is caused to rotate the tool socket through a relatively small angle. With each recurring blow the 100 drill is struck to do useful work and at the same time is rotated so that it will not strike the same place twice in succession.

By employing a rotating chuck of this character to rotate the drill while drilling 110 holes in stone or concrete, the operator is permitted to devote his entire attention to holding and supporting the hammer at the proper position at which he desires to work. By means of the present chuck a working 115 blow from the percussive machine is transformed into a direct working stroke and a turning torque on the drill.

While I have shown a preferred form of structure embodying my invention, structural modifications may be made therein without departing from the spirit and scope 120 of my invention as set forth in the appended claims.

I claim as my invention:

1. A rotating chuck for a percussive machine comprising an impact element, a tool holder adapted to hold a working tool in the path of movement of the impact element, means responsive to a forward movement 130

of the impact element for imparting a rotative movement to the tool holder, and means for normally maintaining a spaced relation between the impact element and the tool holder.

2. A rotating chuck for a percussive machine comprising an impact element, a tool holder adapted to hold a working tool in the path of movement of the impact element, means controlled by movement of the impact element for rotating the tool holder, and a spring disposed between the impact element and the tool holder of sufficient strength to support a percussive machine on the chuck and to preclude the mere weight of the machine from forcing the impact element down upon the tool holder.

3. A rotating chuck for percussive tools comprising an impact element, an enclosing housing disposed thereon, facing in the direction of impact, a bearing threaded into the open end of the housing, a tool socket extending through the bearing into the housing, a spring for normally maintaining a spaced relation between the housing and the tool socket, and means responsive to a change in such spaced relation for turning the tool socket.

4. A rotating chuck for use with percussive machines, comprising an impact element provided with an impact receiving surface and an impact delivering surface, a cup threaded onto said element behind the impact delivering surface and facing in the direction of impact, a bearing disposed at the open end of the cup, a tool socket extending through the bearing into the cup and provided with an impact receiving surface and a toothed circular end surface, a spring surrounding the impact element and normally maintaining a spaced relation between the impact delivering surface of the impact element and the impact receiving surface of the tool socket, and a pawl disposed on the inside of the cup to engage the toothed end surface of the tool socket and arranged to turn the socket each time the impact element strikes the socket.

5. A rotating chuck for use with percussive tools comprising an anvil, a housing therefor, a bearing in the forward end of the housing, a tool socket extending through the bearing and spaced from the anvil striking surface, a spring for normally maintaining such spaced relationship, and means cooperating with the housing and the tool socket for rotating the socket as the anvil strikes the socket.

6. A drill chuck for use with percussive tools, comprising a drill holder, an element for receiving the impact of the percussive tool, means for translating a portion of the energy of impact to produce a turning torque on the drill holder, and means for returning

said impact element to normal position between impacts of the percussive tool.

7. A chuck for effecting intermittent rotative movements of a tool comprising an impact element terminating in a member adapted to be detachably associated with a percussive machine in the path of its reciprocatory member, a tool holder rotatably mounted on said impact element, said tool holder having a surface for receiving direct impact of said element, and means responsive to impact upon said impact element for rotating said tool holder.

8. A chuck for effecting intermittent rotative movements of a tool comprising an impact element terminating in a member adapted to be detachably associated with a percussive machine in the path of its reciprocatory member, a tool holder carried by said impact element and movable longitudinally and rotatably with respect thereto, said tool holder having a surface for receiving direct impact of said element, and means responsive to impact upon said impact element for rotating said tool holder.

9. A chuck for effecting intermittent rotative movements of a tool comprising an impact element terminating in a shank adapted to be detachably associated with a percussive machine in the path of its reciprocatory member, a tool holder carried by said impact element and movable longitudinally and rotatably with respect thereto, a spring interposed between said impact element and tool holder, and means responsive to impact upon said impact element for rotating said tool holder.

10. A chuck for effecting intermittent rotative movements of a tool comprising an impact element terminating in a shank adapted to be associated with a percussive machine in the path of its reciprocatory member, a tool holder carried by said impact element and movable longitudinally and rotatably with respect thereto, a spring interposed between said impact element and tool holder, and means comprising pawl and ratchet mechanism responsive to impact upon said impact element for rotating said tool holder.

11. A chuck for effecting intermittent rotative movements of a tool comprising an impact element having a skirt and terminating in a shank adapted to be detachably associated with a percussive machine in the path of its reciprocatory member, a tool holder comprising a sleeve mounted within said skirt and movable longitudinally and rotatably with respect thereto, a spring confined within said skirt between said impact element and tool holder, and means responsive to impact upon said impact element for rotating said tool holder.

12. The combination with a percussive

- machine and its reciprocatory core member, and rotatably with respect thereto, ratchet of a chuck for effecting intermittent rotative teeth on said tool holder, a pawl co-acting 20 movements of a tool comprising an impact therewith carried by said impact element, element reciprocated by said core member, and a coil spring confined between said impact element and tool holder.
- 5 a tool holder carried by said impact element and movable longitudinally and rotatably with respect thereto, said tool holder having a surface for receiving direct impact of said 25 element, and co-acting pawl and ratchet
- 10 mechanism for imparting intermittent rotative movement of said tool holder.
13. The combination with a percussive machine and its reciprocatory core member, of a chuck for effecting intermittent 30
- 15 movements of a tool comprising an impact element reciprocated by said core member and having a skirt, a tool holder mounted in said skirt and movable longitudinally

14. A chuck for use in combination with a percussive device, comprising a tool 25 holder, an impact element for directly striking said tool holder and transmitting concussive force thereto, and means other than said impact-transmitting means, for engaging said tool holder and imparting 30 relative motion thereto during the force transmitting stroke of said impact element.

In testimony whereof, I have hereunto subscribed my name this 5th day of November, 1924.

GEORGE T. CHAPMAN.
